UNITED STATES PATENT OFFICE.

THOMAS MORANCY, OF ST. PAUL, MINNESOTA, ASSIGNOR TO CHARLES FFOLLIOTT,
OF ST. PAUL, MINNESOTA.

TRACK-LAYING MACHINE.

1,050,375.

Specification of Letters Patent.

Patented Jan. 14, 1913.

Application filed July 10, 1911. Serial No. 637,677.

To all whom it may concern:

Be it known that I, THOMAS MORANCY, a subject of the King of Great Britain and Ireland, residing at St. Paul, in the county 5 of Ramsey and State of Minnesota, have invented certain new and useful Improvements in Track-Laying Machines, of which the following is a specification.

My invention relates to improvements in 10 track laying machines of that class in which the ties and rails are carried on carriers from the supply car to where the tracks are being laid, and has for its object to provide improved means for turning the ties and unloading them sidewise upon the road-bed in 15 the position in which they are to be laid, and also for supporting the tie-carrier high enough above the ground to permit the track layers to work under it.

20 To this end the invention consists in the construction, combination, and arrangement of parts hereinafter described and claimed.

In the accompanying drawings forming 25 part of this invention, Figure 1 is a side view of the machine; Fig. 2 is a plan view of a fragment of the conveyer chains at the receiving end of the tie carrier; Fig. 3 is a top view of the machine with the receiving end partly broken away; Fig. 4 is a plan 30 view of a fragment of the receiving end of the machine; Fig. 5 is a perspective view of the couplings for the carrier rails; Fig. 6 is a top view of the forward or discharge end 35 of the machine, broken away; Fig. 7 is a perspective view of the machine on a reduced scale showing the operation of track laying in connection therewith; Fig. 8 is a perspective view of the tie unloading conveyer at the discharge end of the machine; Fig. 9 is a perspective view of the forward 40 or unloading end of the machine, partly broken away; and Fig. 10 is a cross section on line α — α of Fig. 9.

In the drawings A represents an ordinary 45 flat car designed to be coupled to the forward end of the supply train (not shown). Upon this car is supported the rail and tie carrying apparatus hereinafter described. This apparatus comprises a rail carrier B supported upon one side of the car at about 50 the level of the car platform, and a tie carrier C supported at a much higher elevation upon the opposite side of the car. These carriers may comprise any desired number 55 of carrier sections coupled together by suit-

able means, such as the couplings 2 shown in Fig. 5.

The tie carrier C rises upon an incline from the rear end of the car A, where it is at about the level of the platform, until it reaches a much higher level. It then extends forward at this elevation to the forward end of the machine. It is supported upon struts 3 on the side of the car and a bracket 4 on the post 5. This post is one of 60 the side members of an upright frame D upon the forward end of the car. The portion of the tie carrier which extends forward from this car is supported upon a beam 6 extending upwardly and forwardly 65 from the forward end of the car platform near the post 5. The outer or forward end of this beam is supported from the top of the frame D by means of guy rods 7 and 8. On the opposite side of the machine a beam 9 70 extends forward from the post 10 of the frame D at about the level of the tie carrier, and upon the forward ends of these two beams is supported the unloading apparatus 75 hereinafter described. The forward end of the beam 9 is supported from the boom 12 by means of a guy rod 11. This boom extends upwardly and forwardly from the front end of the car near the post 10, and is supported from the top of the frame D by 80 means of a guy rod 13. The boom also supports the forward end of the rail carrier B by means of a hanger 14.

Each of the carriers B and C has a pair of spaced side rails 15. Between the side rails 90 of the carrier B are journaled rollers 16, which are driven from the shaft 17 of the windlass 18 by means of sprocket and chain or other suitable operative connections, the windlass itself being driven from an engine 95 F upon the flat car. Likewise, between the side rails of the tie carrier C are journaled rollers 19, but those rollers which are in the inclined section of the carrier are not positively driven.

The ties are carried up the incline at the receiving end of the tie carrier C by means of a conveyer consisting of a pair of spaced chains 20 tied together by means of bars 21. These chains pass over sprockets 22 at the 105 receiving end of the carrier, and sprockets 23 arranged near the top of the incline, and work over the rollers 19 upon the inside of the side rails. The sprockets 23 are driven by means of a chain 24 from a sprocket 31 110

upon the windlass shaft 17. On the shaft of the sprockets 23 is a sprocket 25 which has chain connection 26 with the shaft of the adjacent roller 19. And likewise each of the 5 succeeding rollers is operatively connected with the one before by means of sprocket and chain connection.

The rails are unloaded from the carrier B by means of a hoisting cable 53 which passes 10 over a pulley 54 upon the end of a boom 27. This boom has pivotal support 28 upon the front end of the flat car so that it can be 15 swung from side to side.

The ties are carried endwise or lengthwise 20 along the carrier C, so that in order to lay them in place across the road-bed, they must be turned at right angles with their course along the carrier. This can be done manually by the workmen after the ties have 25 been unloaded, but in the present machine there is provided apparatus for first turning the ties and then unloading them sidewise from the end of the machine so that they will drop in place upon the road-bed. This 30 apparatus is supported upon the front ends of the beams 6 and 9 which are connected by means of cross bars 29 and 30 so as to form an unloading table.

Near the forward end of the tie carrier, 35 the carrier rails 4 are spread divergently in order to enable the ties to be turned and deflected. Near the beginning of the divergent portion of the carrier rails is a roller 32 having spikes or prongs adapted to engage the 40 ties and force them along. This roller is driven from the preceding roller 19 by means of the sprocket and chain connection hereinbefore mentioned. Forward of the spiked roller 32 is a screw or worm 33 journaled in the side rails and having left handed threads, so that the ties in passing over it will be deflected outwardly away from the machine, while farther in advance is a worm or screw 45 34 also journaled in the side rails and having right handed threads, so as to deflect and turn the logs inwardly toward the unloading table at the front of the machine. The worm 34 is driven from the worm 33 by means of the sprocket chain 35, while the 50 worm 33 is driven from the spiked roller 32 by means of a sprocket chain 56. Thus when a tie is forced forward by the spiked roller, it will be turned first outwardly by means of the worm 33 and then inwardly by means 55 of the worm 34, as indicated in dotted lines in Fig. 6, where the worm 33 is shown forcing the rear end of the tie outwardly while the worm 34 is forcing the forward end inwardly, the two worms thus co-operating to 60 turn the tie around. In order to prevent the ties from leaving the carrier, as well as to assist in guiding their course, a curved shield 36 is secured across the end of the carrier. It will be seen that the ties are thus forced 65 over from the tie carrier on to the unloading

table formed by the cross bars 29 and 30, and a diagonal bar 43. Having journal support upon the bars 30 and 43 at the side of the tie carrier is a spiked roller 37 rotatable upon an axis lengthwise of the machine and transverse to the axes of the roller 32 and the worms 33 and 34. This roller 37 is 70 driven from the worm 33 by means of the bevel gears 38. Also journaled upon the bars 30 and 43 at suitable distances apart and rotatable on axes parallel with that of the roller 37 are three screws or worms 39, 40, and 41, and between the worms 40 and 41 is a roller 44. The worm 39 is driven from the shaft of the spiked roller 37 by 75 means of sprocket and chain connection 42, and each of the succeeding worms and rollers is driven from the one before it by means of a similar sprocket and chain connection. Thus when the ties have been delivered upon 80 the unloading table, the screws 39, 40, and 41 will force them sidewise off the end thereof. As will be seen from Fig. 10 the worms 39, 40, and 41 are arranged at a lower level than the spiked roller 37 and the side rail of 85 the tie carrier, so that the tie, when once delivered to the worms, cannot work back onto 90 the carrier. And to prevent the ties from leaving the rear end of the unloading table, as well as to assist in turning them, a shield 95 45 with a curved outer end is extended diagonally across the table. As the unloading table is at a considerable elevation above the ground, the ties are lowered by means of the unloading carrier shown in Fig. 8 of the 100 drawings. This carrier comprises a frame E which is secured to the unloading table by means of hinge straps 46 at the top and a brace 55 at the bottom. Upon this frame are journaled spaced sprocket wheels 47 at the 105 top and 48 at the bottom. Over these wheels run two conveyer chains 49 carrying at suitable intervals tie rests 50, the tie rests on one chain corresponding in position with the tie rests on the other. The lower sprocket 110 wheels 48 are fast upon a common shaft 51. Upon this shaft is a brake pulley 52 engageable by a brake strap 53 operated by a 115 brake lever 54, whereby the speed of travel of the conveyer chains can be checked and regulated. When the ties are discharged 120 sidewise from the end of the unloading table, they will drop over upon the tie rests, as illustrated in Fig. 1, and their weight will cause the chains to move down until the tie 125 rests turn from their horizontal position and permit the ties to drop upon the ground.

In operation, the ties are carried up endwise along the tie carrier C, as described. When they reach the worms 33 and 34 they 125 will be turned endwise by these worms and forced onto the unloading table, where they will be seized by the spiked roller 37 and carried onto the screws 39, 40, and 41. These screws or worms will then force the ties 130

sidewise off the end of the unloading table onto the tie rests of the unloading carrier, by means of which they will be lowered gradually to the ground across the road-bed 5 in position to receive the rails. The rails are at the same time carried along the carrier B, from the forward end of which they can be unloaded by means of the hoisting rope 53, and laid upon the ties. By having 10 the tie carrier elevated a considerable distance above the rail carrier, the workmen can lay the rails and work under it to excellent advantage as illustrated in Fig. 7.

I claim as my invention:

15 1. In a track laying machine, the combination with a construction car, of a tie carrier supported along one side of the car and extending forwardly beyond the same, a power driven worm disposed transversely of 20 the carrier at the forward end thereof and adapted to deflect the advancing ties, an unloading table arranged at one side of the forward end of the carrier in position to receive the deflected ties, and power actuated 25 means arranged upon the unloading table for forcing the ties sidewise off the end thereof.

2. In a track laying machine, the combination with a construction car, of a tie carrier arranged along one side of the car and extending forwardly beyond the same, said carrier being adapted to carry the ties in lengthwise position, a worm rotatable upon a transverse horizontal axis at the forward 30 end of the carrier and adapted to turn the advancing ties to one side, an unloading table arranged at the side of the forward end of the carrier in position to receive the deflected ties, and power driven worms journaled upon the unloading table and rotatable upon longitudinal horizontal axes, said worms being adapted to work the ties sidewise off the end of the unloading table.

3. In a track laying machine, the combination with a construction car, of a tie carrier supported upon the car at a rising incline and extending at an elevation beyond the forward end of the car, said carrier being adapted to hold the ties in lengthwise 45 position, an endless conveyer working along the incline for elevating the ties, means arranged at the forward end of the carrier for turning the ties from lengthwise to sidewise position, and an unloading carrier extending down from the front end of the machine, said unloading carrier being adapted to receive the ties and lower them to the ground.

4. In a track laying machine, the combination with a construction car, of a tie carrier supported along one side of the car and extending forwardly beyond the same at an elevation, said carrier being adapted to carry the ties endwise, means arranged at 60 the forward end of the carrier for deflect-

ing the ties from endwise to sidewise position, an unloading table supported at the forward end of the carrier and at one side thereof in position to receive the deflected ties, power actuated means for forcing the 70 ties sidewise off the end of said table, an endless conveyer hung from the end of the unloading table and having rests to hold the ties, and means for regulating the travel of the conveyer.

5. In a track laying machine, the combination with a construction car, of a tie carrier supported along one side of the car and extending forwardly beyond the same, the carrier comprising spaced side rails and rollers journaled therein, the side rails at the forward end of the carrier being made divergent, oppositely threaded worms journaled in the rails of the divergent portion of the carrier and adapted to turn the ties to one side, an unloading table arranged at one side of the forward end of the carrier in position to receive the deflected ties, and power driven worms journaled on the table and rotatable upon a longitudinal horizontal axis, 80 said worms being adapted to work the ties sidewise off the end of the table.

6. In a track laying machine, the combination with a construction car, of a tie carrier supported along one side of the car and 95 extending forwardly beyond the same, a power driven worm disposed transversely of the carrier at the forward end thereof and adapted to deflect the advancing ties, an unloading table arranged at the side of the forward end of the carrier, in position to receive the deflected ties, a spiked roller journaled upon the unloading table and rotatable upon an axis transverse to the axis of said worm, and power driven worms journaled upon the unloading table at the side of the spiked roller and rotatable upon axes parallel with the axis of said roller, said worms being arranged upon a lower level 100 than the spiked roller.

7. In a track laying machine, the combination with a construction car, of a tie carrier supported along one side of the car and extending forwardly beyond the same, oppositely threaded worms arranged transversely of the carrier at the forward end thereof and adapted to turn the ties to one side and power driven unloading worms arranged at the side of the forward end of the carrier in position to receive the deflected ties, said unloading worms being journaled upon axes transverse to the axes of said oppositely threaded worms, and being adapted to work the ties sidewise off the end of the machine.

8. In a track laying machine, the combination with a construction car, of a tie carrier supported along one side of the car, oppositely threaded worms disposed transversely of the carrier at the forward end 120 130

thereof and adapted to turn the ties to one side, and power driven means in position to receive the deflected ties and adapted to work them sidewise off the forward end of 5 the machine.

9. In a track laying machine, the combination with a construction car, of a tie carrier supported at an elevation along one side of the car and forwardly beyond the 10 same, said carrier being adapted to carry the ties endwise, means at the forward end of the carrier for turning the ties from endwise to sidewise position, power actuated means for discharging the ties sidewise off 15 the end of the machine, and a conveyer at the end of the machine and adapted to receive and lower the discharged ties.

10. In a track laying machine, the combination with a construction car, of a tie carrier supported upon the car and adapted to carry ties in lengthwise position, and a worm element arranged at the forward end of the carrier in the path of the advancing ties and adapted to turn the ties transversely 25 to the carrier.

11. In a track laying machine, the combination with a construction car, of a tie carrier supported upon the car and adapted to carry ties in lengthwise position, and oppositely threaded worms disposed transversely 30 of the carrier at the forward end thereof, whereby to turn the advancing ties transversely to the carrier.

12. In a track laying machine, the combi-

nation with a construction car, of a tie carrier supported at an elevation above the car and extending forwardly beyond the same, and adapted to carry ties endwise, means at the forward end of the carrier for turning the ties sidewise, and means for lowering the 35 ties in sidewise position from the end of the machine.

13. In a track laying machine, the combination with a construction car, of a tie carrier extending at an elevation beyond the 40 forward end of the car and adapted to carry ties endwise, means at the forward end of the carrier for turning the ties sidewise, and an unloading conveyer adapted to receive the ties in sidewise position and lower them 45 to the ground.

14. In a track laying machine, the combination with a construction car, of a tie carrier extending at an elevation beyond the 50 forward end of the car and adapted to carry the ties endwise, means at the forward end of the carrier for turning the ties sidewise, an unloading conveyer adapted to receive and hold the ties in sidewise position and lower the same to the ground, and means for 55 regulating the speed of travel of the conveyer.

In testimony whereof I affix my signature in presence of two witnesses.

THOMAS MORANCY.
